(57) **CLAIM**

The design for a tire valve tool, as shown and described.

DESCRIPTION

FIG. 1 is a perspective view of a tire valve tool, showing my new design;

FIG. 2 is a top plan view thereof;

FIG. 3 is a left side elevational view thereof;

FIG. 4 is a right side elevational view thereof; and,

FIG. 5 is a cross section view taken along line 5—5 in FIG. 1.
